UNITED STATES PATENT OFFICE.

WILLIAM G. AHRENDT, OF NEWARK, NEW JERSEY.

BELT-BUCKLE.

1,354,450.

Specification of Letters Patent. Patented Sept. 28, 1920.

Application filed February 18, 1920. Serial No. 359,636.

To all whom it may concern:

Be it known that I, WILLIAM G. AHRENDT, a citizen of the United States, and a resident of Newark, in the county of Essex and State 5 of New Jersey, have invented a new and Improved Belt-Buckle, of which the following is a description.

My invention relates to belt buckles and more particularly relates to the type of belt 10 buckle in which a gripping element is arranged to have sliding movement longitudinally of the buckle for effecting a gripping action on the belt.

The general object of the invention is to 15 provide a buckle of the indicated type improved in various particulars, more especially with respect to the belt-gripping means, more specific objects being to provide a buckle of simple form possessing strength 20 and presenting an attractive appearance when worn.

The nature of the invention and its advantages will clearly appear from the specific description following.

25 Reference is to be had to the accompanying drawings forming a part of this specification, it being understood that the drawings are merely illustrative of one example of the invention.

30 Figure 1 is a front view of the belt buckle embodying my invention, showing the same applied to a belt shown in part;

Fig. 2 represents a horizontal section of the buckle, a portion of the belt being 35 shown;

Fig. 3 is a cross section through the buckle on the line 3—3, Fig. 1, the belt being omitted;

Fig. 4 is a rear view of the buckle.

40 In carrying out my invention in accordance with the illustrated example, the buckle body is formed with a face plate 10 which may be of any approved design, said plate being here shown as substantially plain.

45 The material forming the buckle is returned rearwardly integral with the face plate 10 to produce longitudinal side members 11 which preferably are somewhat convergent rearwardly, the material being continued laterally at the back of the buckle and formed to present longitudinal flat side bars 12 integral with the sides 11. The buckle body is made tapering or at all events is made to present an interior passageway for 50 the belt A, convergent toward that end 13

receiving the free end of the belt, to be adjustably secured; this is brought about in the illustrated example by giving the buckle body a wedge-like form, so that it tapers bodily toward the end 13.

In connection with the body as described I arrange a slide 14 consisting of a back plate or base lying at the back of the buckle, that is to say, outside of the rear longitudinal bars 12 and said slide at its inner side is given a formation to engage and grip the belt A when the latter is passed through the buckle body. In the form shown the slide is formed with a transverse element 15 applied to the inner side thereof and protruding into the interior of the buckle to lie in the passageway of the belt. The inner surface of member 15 in the preferred form of the invention is of such a character as to cause the slide to engage and grip the belt along a 70 definite line or lines, the illustrated example presenting tapered surfaces convergent along approximately the medial line of the slide. The buckle body is formed at one end with a cross bar 18 forming a tie between 75 the flat back bars 12 and in the same plane therewith, and thereby strengthening the buckle, besides constituting a stop limiting the movement of the slide 14 in one direction.

80 The slide 14 presents lateral slots or recesses 16 at the ends of the gripping element 15, so that the ends of the element overlap the back bars 12 at the inner sides of the latter and the base plate of the slide 85 or back of the slide 14 overlaps said back bars 12 and extends slightly beyond the same and therefore slightly beyond the inner edges of the sides 11 of the buckle body. Thus, the slide engages the bars 12 both at 90 the interior of the buckle and at the exterior and in a manner that the slide is constrained to have a parallel movement and is prevented from assuming an angle that would cause it to bind at its end against the 95 buckle body.

100 The loop 19 about which the belt is returned at one end as at B and the buckle made fast to the belt, is formed with a tubular attaching member 20, the ends of which 105 receive inwardly directed tongues 21 constituting trunnions for said loop, said tongues being produced by forming lateral slots or recesses 22 in the back bars 12, the material of the buckle being sufficiently 110

bendable to force or spring the tongues 21 into the ends of the tubular ends of said attaching member 20.

It will be obvious from the foregoing that the gripping action of the slide is brought about in a very simple manner and by a very simple construction because of the tapering interior or belt passage-way and this being due in the preferred form 10 as illustrated by the tapering of the buckle body itself as distinguished from the formation of inclined slots or similar inclined guideways formed in the sides of the buckle body. Moreover, by the arrangement shown 15 the slide 14 may be gripped in either of two ways, that is to say, the thumb may grasp the slide at the back surface when the thumb is passed to the back of the buckle, or the slide may be grasped by its 20 opposite projecting ends 17, and operated for releasing the belt, the convergent forms of the sides 11 of the buckle body contributing to the facility with which this last-mentioned manner of operating the slide may 25 be brought about. It will be clear also, that the strength of the buckle body is not decreased in co-ordinating it with the gripping slide.

I would state in conclusion that while the 30 illustrated example constitutes a practical embodiment of my invention, I do not limit myself strictly to the mechanical details herein illustrated, since manifestly the same can be considerably varied without departure from the spirit of the invention, as defined in the appended claims.

Having thus described my invention, I claim:

1. A belt buckle including a body presenting an interior longitudinal passageway for the belt, said passageway being tapered toward one end, and a slide having a substantially flat back plate disposed in a plane in the rear of the plane of the back of said 40 body and extending to the sides of the latter that its ends may be grasped for manipulating the blade, said ends between the front and back edges of the plate presenting depressions for the grasping of the plate 45 and said plate being in substantially the same plane throughout, said slide presenting a portion protruding into said passageway for engagement with the belt.

2. A belt buckle including a body presenting an interior longitudinal passageway for the belt, said passageway being tapered toward one end, said body having sides thereof in planes converging rearwardly, a transversely disposed slide on said 50 body at the back thereof and having guided longitudinal movement on said body adjacent to the sides, said slide having a back plate, the ends of which project beyond the sides of the body to be grasped by the user, 55 said plate and its projecting ends being in

substantially the same plane throughout and in the rear of said body, said slide having a member protruding into said passageway for gripping the belt.

3. A belt buckle including a body presenting an interior longitudinal passageway for the belt, said passageway being tapered toward one end, and a slide presenting a transverse back plate disposed in a plane rearward of the back of the body presenting a surface to be engaged by a finger passed behind the body, and means on said slide and protruding into said passageway for engagement with the belt, said back plate lying substantially in one plane 80 throughout and extending at its sides to the planes of the outer surfaces of the sides of the body for convenient gripping.

4. A belt buckle including a body presenting sides in rearwardly convergent planes, 85 said body presenting a longitudinal passageway for the belt, said passageway being convergent toward an end of the body, and longitudinal bars rigid with said sides at the back of the buckle, a slide presenting a back 90 plate in substantially a single plane extending transversely of the buckle in the rear thereof the ends of said plate overlapping said back bars to have longitudinal movement thereon, and gripping means on said 95 slide within the buckle body and overlapping said bars at the interior of the buckle.

5. A belt buckle including a body having at the back thereof side members presenting laterally disposed slots at one end, and members similarly disposed and constituting trunnions, and a belt-attaching loop having a tubular member receiving said trunnions in the ends thereof.

6. A buckle including a body having at 105 the back thereof longitudinally disposed flat side bars and presenting an opening therebetween leading to the interior of the buckle, said interior presenting a longitudinal passageway for the belt, said passageway being convergent toward one end, a slide movable longitudinally of said body and extending into the interior of the buckle to engage a belt, said side members adjacent to said end being transversely slotted and presenting trunnion members at said slots disposed laterally inward toward each other, and a belt-attaching loop having the inner portion 110 thereof presenting tubular ends into which said trunnion members extend.

7. A belt buckle including a body affording a longitudinal passage for the belt and presenting longitudinal side bars at the back of the buckle, and a transversely disposed slide on said body at the back adapted to 120 grip the belt, the ends of said slide being slotted and accommodating said side bars.

8. A belt buckle including a body affording a longitudinal passage for the belt and presenting convergent sides terminating in 130

edge portions directed laterally inward and forming longitudinal guide bars disposed in the plane of the back of the body, and a slide on said body including a transverse back plate in the rear of said guide bar and overlapping the latter so that those edges adjacent to said convergent sides are directly accessible at said sides for grip-

ping, to move said slide, there being a transverse gripping member on said back plate at 10 the inner side thereof and lying in said passage, said gripping member extending to the sides of the body and under said guide bars, said gripping member having slots therein slidably receiving said guide bars.

WILLIAM G. AHRENDT.
